MAGNETIC PICKUP DEVICE

Joseph C. Adams, East Orange, N. J., assignor to
 Thomas A. Edison, Incorporated, West Orange,
 N. J., a corporation of New Jersey

Application October 29, 1942, Serial No. 463,798

10 Claims. (Cl. 179—2)

This invention relates to a magnetic pick-up device of the type adapted for response to a magnetic field, and has especial relation to magnetic pick-up devices adapted for picking up signal energy from telephone systems as for the purpose of coupling a phonographic recorder or loud-speaking system to a telephone.

It is an object of my invention to provide a magnetic pick-up device having an improved efficiency.

It is another object to provide an improved magnetic pick-up device which is selectively responsive to magnetic fields of different divergence—that is to fields originating from sources at different distances.

It is another object to provide a selective magnetic pick-up unit the parts of which do not require to be individually adjusted or positioned relative to the magnetic fields which are to be selected between.

It is another object to provide a selective magnetic pick-up device in a unitary form which does not require a critical positioning of the unit relative to the magnetic fields which are to be selected between.

It is a further object to provide a magnetic pick-up unit which is effective, when placed adjacent to a telephone box containing the standard telephone induction coil, to pick up signal energy from the telephone system with an improved signal to noise ratio.

It is a still further object to provide a magnetic pick-up unit which is especially adapted for conveniently picking up telephonic voice signals from hand combination telephone sets.

Other and allied objects of my invention will more fully appear from the following description and the appended claims.

In the description of my invention reference is had to the accompanying drawing of which:

Figure 1 is a side view, partly broken away, of a hand combination telephone set showing the pick-up device of my invention associated therewith for picking up signals from the telephone induction coil;

Figure 2 is a perspective view showing a proper positioning of the pick-up coils of my device relative to a telephone induction coil;

Figure 3 is a top plan view, with parts broken away, of the pick-up device according to my invention;

Figure 4 is an enlarged fractional sectional view taken on the lines 4—4 of Figure 3; and

Figure 5 is a schematic circuit diagram of my pick-up device and of a typical load therefor.

Magnetic pick-up devices for inductively coupling electrical apparatus such as a phonographic recorder or loudspeaking system to a telephone system are well known in the art. Ordinarily these pick-up devices are placed on or adjacent to the telephone box where they will be linked by the stray flux of the standard induction coil of the telephone equipment. The telephone box may be either on the wall or within the base portion of a desk set such as is the case with the hand combination set commonly used. In either case though the magnetic shielding provided by the box container prevents efficient coupling of the pick-up device with the telephone system and, as a result, a low level of signal pick-up is obtained. In fact, often stray fields of electrical machinery or apparatus in the vicinity are comparable in strength to the available signal field from the telephone system, and noise pick-up is a serious problem. To subdue however the noise pick-up, there has been provided a magnetic pick-up device of a dual form comprising two electrically connected but separately positionable pick-up coils. One of these coils is placed in the signal field from the telephone system but the other is placed substantially out of that field and so oriented with respect to the noise field as to neutralize the noise flux-currents picked up by the other coil.

10 Magnetic telephone pick-up devices as heretofore provided have however not been very satisfactory in that they have been wanting for a better signal to noise ratio of pick-up—this being especially true when picking up from a closed core type of telephone induction coil—and have been large and bulky, making them difficult to mount. Moreover, it has been a disadvantage of those of the dual form that they have required a separate and critical relative positioning of the pick-up coils. I have found however that these deficiencies can be largely overcome by the use of long slender solenoidal type coils. These coils are wound on magnetic cores which have their several dimensions in cross section substantially 20 equal, or varying at most by no more than a ratio of 2:1. Preferably, I use magnetic cores having a large ratio of length to square root of cross-sectional area, as at least of the order of 15 but preferably more, and apply windings on these cores having a radial thickness not substantially greater, but preferably less, than the dimensions in cross section of the core, the coils having a ratio of length to outside diameter which is at least of the order of 5. With such coils, I find 30 that I am enabled to obtain an improved coefficient of coupling between the telephone system and the pick-up device.

client of coupling with the induction coil, whether that coil be in a hand combination set or wall box, or of the substantially closed core type, and that I am especially enabled to realize a small pick-up device in a unitary form which has a substantially improved pick-up ratio of signal to noise without need for separate positioning of its several coils or of critical positioning of the unit as a whole.

In a preferred form of my invention shown in Figures 3 and 4, which is of the dual form above-noted, there are provided two coils 1 and 1a. These coils are made substantially identical, within the tolerances of ordinary manufacturing practice, and are mounted on laminated cores 2 and 2a made for example of silicon steel. Each coil is covered with a fold of electrostatic shielding 3, as of tin foil, but the overlapping ends of the foil are separated by an intervening sheath of insulation 4, as is indicated in Figure 4, this being done so as not to place a short circuit around the coils. Purely by way of example, the pick-up device will be considered to work into an unbalanced load circuit, as into the input of an electrical amplifier, in which case connection may be made to the load by a shielded single conductor lead 6 of which the shield 6' is utilized as a ground return connection, this shield 6' being connected by a lead 7 to one of the coils. By suitable connections not herein necessary to show, the shield 6' is also connected to the coil shields 3 and to the cores 2 and 2a. The coils 1 and 1a are fixedly held in substantially axially parallel relation by a non-magnetic cross piece 18 and respective clamps 11, the clamps being insulated from the coils by insulation wrappings 12 and arranged so as not to short-circuit the coils. This coil arrangement is mounted in a thin-walled non-magnetic container 13, made as of plastic, and is held therein by a screw 14, the container having any suitably removable cover piece 15 and side opening 16 through which the shielded conductor 6 passes. The laminated cores 2 and 2a terminate respectively into shoes 17 and 17a at the coil ends, and these shoes are disposed radially of the coils in parallel relation to one another and extend at least as far as to the periphery of the coils for contact with the cover of the container 13.

The pick-up coils 1 and 1a are to oppose one another as magnetic pick-up elements, and may be connected either in series or in parallel arrangement. I prefer, however, to use the series arrangement and do accordingly interconnect the adjacent ends of the coils by a shielded conductor 5, the shield of which will be understood to be connected to be electrically common with the other shielding elements of the pick-up device. When two identical and axially parallel coils are so serially connected, their pick-up from a given magnetic field will be such that their respectively induced currents will oppose or buck one another. This serial connection and spatially parallel relation of the coils, by which they oppose one another as magnetic pick-up elements, I herein term "a series-opposing one."

For picking up signals from an induction coil 18, the pick-up device may be positioned so that the axes of the coils are parallel to the axis of the induction coil with one of the pick-up coils at a minimum possible distance from the induction coil, as is indicated in Figure 2; yet preferably, however, the pick-up device may be oriented so that the axes of the pick-up coils are parallel to a center line running through the air gaps 28

(with which the magnetic core of the induction coil is provided as is hereinafter explained), with one of the coils being again spaced at a minimum possible distance from the induction coil. This induction coil is a standard element in telephone equipment and may be provided with or without a substantially closed magnetic core. In the present illustrative example, a substantially closed core type of coil is shown having the laminated magnetic core 18 provided with air gaps 28 above-mentioned at the opposite ends thereof, these air gaps being provided to prevent saturation of the core from the D. C. current of the telephone line. Because there is a magnetic potential drop across the coils it necessarily has a stray flux radiation although the radiation is less as the reluctance of the magnetic circuit is reduced, it being very small for the closed core type of coil here illustrated. Accordingly, in picking up from a closed core induction coil, it is highly important that the maximum possible coefficient of coupling be made, that is, that there be obtained a maximum linkage of the pick-up coil with the available stray flux of the induction coil.

To obtain such maximum linkage, the core of the pick-up coil is aligned with the available stray field of the induction coil as by orienting the axis of the pick-up coil in a plane substantially parallel to that of the induction coil. According to my invention I am enabled to obtain a high percentage of flux interlinkage with the pick-up coil by the use of long slender coils having magnetic cores, as this permits the magnetic core of the coil to be placed at a minimum spacing from the induction coil, and also through the length of that coil, where it will provide a low reluctance path for the available stray flux. Moreover, the core shoes which I provide—and which I direct towards the induction coil in the mounting of the pick-up device—serve to reduce the length of air gap, and thus of reluctance, from the ends of the pick-up coil to the induction coil. This has the effect of directing the stray flux through the entire length of core of the pick-up coil to effectively increase the coefficient of coupling and efficiency of pick-up.

I find that the use of long slender pick-up coils is particularly effective for obtaining a pick-up device that is highly selective as to fields originating from sources near and far, or to fields of different divergence, it being understood that fields near their source have a high divergence—that is, a considerable digression from parallelism—and those at a distance from their source have a low divergence. This selectivity arises from the fact that a long magnetic core exercises a high directive influence over the flux in its vicinity, since the flux, in seeking a path of low reluctance, is "taken in" by the core and led along the length thereof, the effect being to bunch and straighten out the flux lines in the vicinity of the coil. Both of the pick-up coils will exercise this directive influence alike and will tend to be interlinked by about the same amount of flux unless the magnetic field has a large divergence. Normally, noise pick-up is from fields of small divergence since the source of the noise, such as a motor, will be at a great distance from the pick-up device compared to that of the pick-up device from the induction coil of the telephone instrument. The pick-up coils will thus tend to pick up approximately the same amount of noise. Moreover, they will tend to do this within a range of relative positioning, as well as of positioning of both the coils alike relative to the noise field, by virtue of the large

directive influence which the coils exercise over the flux in their vicinity. Accordingly, my pick-up device does not require that the coils thereof be separately adjusted nor that the over-all device be critically located in order to effect a low pick-up of noise current originating from sources at a distance.

For maximum pick-up from the telephone system, the pick-up device is so oriented as to obtain the largest possible differential of coupling of its respective coils with the telephone induction coil. For instance, one coil may be placed directly below the induction coil, or be shifted from that position in the direction which will increase the spacing of both the coils from the induction coil, a suitable positioning of the pick-up coils relative to the induction coil being, for instance, shown in Figure 2.

It will be understood a substantial spacing must be had between the pick-up coils 1 and $1a$ in order that a substantial differential in coupling of the coils with any nearby flux source may be had. Yet the distance of spacing must not be too great to result in any substantial difference in coupling of the coils with a relatively distant flux source. As a typical case, the spacing between coils is about half of their length. For example, the coils are preferably made about $3\frac{1}{2}$ long and spaced about $1\frac{1}{2}$ " apart, and are provided with an outside diameter of about $\frac{5}{16}$ ". As for the cores, they are preferably made about square in cross section with a dimension of about $\frac{1}{8}$ " at each side, and the shoes thereof are each made about $\frac{3}{4}$ " long.

Because of the very low coefficient of coupling of the pick-up device with the telephone induction coil, the frequency response characteristic of the device is determined substantially wholly by the relative values of the impedance elements in the circuit in which the device works, this circuit being hereinafter termed the work circuit. For example, the pick-up device may work directly into the grid of an amplifier tube 23 , and across a suitable grid leak resistance 24 , as is shown in Figure 5. According to my invention this work circuit is arranged or tuned to have a natural resonant frequency within the middle vocal frequency range, as at a frequency between 1200 to 2000 cycles. Preferably, I employ high impedance pick-up coils having many turns of fine wire and control the winding space factor of the coils so that their effective internal distributed capacity plus the capacity of the shielded leads to the coils—which total capacity is referred to as 25 in Figure 5—will in combination with the inductance of the coils give the desired natural resonant frequency. Of course the distributed capacity 25 may be supplemented by a lumped external capacity, if desired. In tuning the pick-up device, though, I preferably choose relative values of resistance to reactance which will obtain a very mild accentuation in response of the pick-up device at its resonant frequency. Typically, I find that an accentuation of from 3 to 6 db's. at the resonant frequency over that obtained at one octave from the resonant frequency is satisfactory.

It will be noted that the pick-up device which I provide is very well adapted for picking up telephonic voice signals from hand combination telephone sets. For instance, the device may be conveniently inserted in the space 21 normally provided below the usual hand combination set 22 as is shown in Figure 1. As so placed, the pick-up device is very desirably out of view where it will not deface the appearance of the telephone instrument. Yet the pick-up device may be conven-

iently oriented for maximum coupling with the telephone induction coil merely by shifting it horizontally below the hand combination set.

While my invention has especial utility and is herein illustrated and described as a telephone pick-up device, it will also be understood that various changes and modifications may be made in the embodiment herein disclosed without departing from the scope of my invention, which I endeavor to express according to the following claims.

I claim:

1. A magnetic pick-up device for response to the stray field of an induction coil, comprising a solenoidal type pick-up coil having a magnetic core, said core having a ratio of length to square root of cross-sectional area which is at least of the order of 15.

2. A magnetic pick-up device for response to the stray field of an induction coil, comprising a solenoidal type pick-up coil having a magnetic core, said core having a ratio of length to square root of cross-sectional area which is at least of the order of 15.

3. A magnetic pick-up device selectively responsive to magnetic fields of different divergence, comprising a pair of pick-up coils having magnetic cores, said coils being spacedly held in substantially parallel relationship and arranged magnetically opposing, and said coils being of the solenoidal type.

4. A magnetic pick-up device for response to the stray field of an induction coil and adapted to be substantially unresponsive to fields originating from sources relatively distant, comprising a pair of solenoidal type coils having magnetic cores, said coils being fixedly held in a substantially parallel relationship and arranged magnetically opposing, and the length of said coils being substantially twice the distance of spacing between the coils.

5. A magnetically selective pick-up device comprising a pair of magnetic core solenoidal type coils fixedly held in a substantially parallel relationship and connected series-opposing, said coils having a substantial spacing from one another relative to their lengths, and the ratio of the lengths of said coils to their outside diameters being at least a several times multiple of unity.

6. A magnetic pick-up device for response to the stray field of an induction coil and adapted to be substantially unresponsive to fields originating from sources relatively distant, comprising a pair of solenoidal type coils having magnetic cores and arranged magnetically opposing, the ratio of length to square root of cross section area of said coils being at least of the order of 15.

7. A magnetic pick-up device for response to the stray field of an induction coil and adapted to be substantially unresponsive to fields originating from sources relatively distant, comprising a pair of solenoidal type coils arranged magnetically opposing, said coils having magnetic cores provided with shoes at the core ends, said shoes extending radially of the coils at least to the peripheral surfaces of the coils.

8. A magnetic pick-up device for response to the stray field of an induction coil and adapted to be substantially unresponsive to fields originating from sources relatively distant, comprising a pair of solenoidal type coils spacedly held in substantially parallel relationship and arranged magnetically opposing, said coils having magnetic cores provided with shoes at the core ends, said shoes extending radially of the coils in a direc-

tion substantially normal to the plane through the axes of the coils.

9. In combination with a substantially closed core type of telephone induction coil, a solenoidal type pick-up coil orientated relative to said induction coil for response to the stray field thereof, and a second solenoidal pick-up coil placed substantially out of the stray field of said induction coil, said pick-up coils being held substantially parallel to one another and arranged magnetically opposing.

10. Apparatus for coupling a phonograph to a

telephone system comprising a telephone box including a telephone induction coil connected in the telephone system; a solenoidal-type pick-up coil mounted adjacent to said box and connected to the phonograph, said pick-up coil being offset radially from said induction coil and having its axis in a plane substantially parallel to the axis of the induction coil, and said pick-up coil having a ratio of length to outside diameter which is at least of the order of 5.
